INVENTOR.
Joel H. Kessler
BY Max D. Ordman
ATTORNEYS.

Applicant claims that his invention relates to a device for the neck portion of a violin, which device is adapted to be applied to the neck portion of a violin and which device is adapted to maintain the hand and wrist of the violinist in the correct and natural position.

UNITED STATES PATENT OFFICE

JOEL H. KESSLER, OF BROOKLYN, NEW YORK

VIOIN ATTACHMENT

Application filed January 5, 1931. Serial No. 506,592.

This invention relates to stringed instruments such as violins and particularly an attachment member for the violin and has for one of its objects to provide a device which will serve as a guide for the hand of the pupil so as to maintain the hand and wrist in the correct and natural position.

Several braces have been hitherto known having the same object but which have the drawback that while they support the wrist in a certain position they do not prevent the turning of the hand itself as a result of which the pupil is unable to acquire the habit of maintaining the hand always in the correct position.

The known devices also have the drawback that they actually embrace the hand or wrist and this has been found to be undesirable, inasmuch as such embracing feels very uncomfortable and has the tendency to paralyze the muscles of the hand or fingers.

This invention has therefore an additional object, to wit, to so construct the device or attachment that it will support the wrist, hand and arm in natural position very comfortably and without exerting any strain on the player.

A further object is to provide a device which may be used for either right or left handed players.

Still another object is to provide a comparatively cheap and simple construction of my device.

With the above and other objects in view my invention comprises the novel construction, combination and arrangement of elements to be hereinafter more fully described, shown and defined in the appended claims.

In the accompanying drawings which form part of this specification and in which similar reference characters denote corresponding parts;

Fig. 1 is a side elevation of my device applied to the neck portion of the violin;

Fig. 2 is a perspective view of the device shown in Fig. 1; and

Fig. 3 is a perspective view of a modified form of my device.

Referring to the drawings, 10 denotes a violin body, 11 the neck portion for said violin body and 12 the head of said neck portion. My device is adapted to be attached to said body 10 and to said head 12 and may comprise a member 13 such as a rod of wood, metal, wire or other suitable material. This member is suspended from the said violin body and from the head 12 by means of double armed members 14, 15, which in the present embodiment consist of wires coiled around the rod 13 as at 14' and 15' and the arms 14a and 15a of each of which extend upwardly. The free ends 14' of the arms 14a are bent over laterally and are designed to hook over the top surface of the body 10, one on each side of the neck 11. The arms 15a at the other end of rod 13 are preferably made of resilient wire so as to clamp around the sides of the head 12. The free ends of these arms 15a may be provided with eyelets or loops 15' for the passage of a screw 16 (Fig. 3) whereby the arms may be tightened to the neck if desired.

Slidably but tightly mounted on said rod 13 between said pairs of supporting members 14a, 15a is a supporting arm 17 which may be also formed of a piece of wire, one end of which is wound around said rod as at 17' and frictionally but slidably engages the same. The said support extends laterally from said rod 13 and towards the body of the violin.

In the modification shown in Fig. 3 the supporting arm 17a which also may be of a loop of wire or any other suitable material has at one end a collar 18 which is slidably mounted on the rod 13. The collar may be fixed in the desired position by means of set screw 19.

In operation, the device is mounted between the body 10 and head 12 below the neck 11 as shown in Fig. 1 and the arm 17 (17a) adjusted on said rod 13 to the position most suitable for the particular player. Then the player after properly positioning the violin grasps the violin neck in the usual manner and places his hand so that his thumb extends between the rod 13 and neck 11 and the inner part of his wrist rests against the arm 17 (17a), while the thumb side of the hand adjoining the wrist bears against part 13' of the rod which extends beyond the support 17 toward the head portion of the neck 11. In this manner the player's hand and arm are steadied in the correct position and while the device permits freedom of movement of the fingers, it prevents the hand from swinging in towards the neck at the wrist portion and also prevents its swinging laterally under the neck. By having member 13 extend between the end of the violin body 10 and the head 12 of the neck portion, I am in a position not only to suspend the device in the most convenient and simple manner, but also to produce a guide that will not grip the wrist or hand of the player, but merely guides the hand and arm and, while permitting free movement of the fingers, hold the hand and arm against moving sideways under the neck and prevent swinging around of the wrist.

The position of the arm 17 (17a) shown is that when the device is used for a right handed player. To adapt the said device for use by a left handed player, it is only necessary to rotate the support arm 17 (17a), 180° about the rod 13 as an axis.

To prevent damage to the violin as by scratching or the like the arms 14 and 15 may be covered with some soft material (not shown). Likewise the support arm 17 (17a) and the rod 13 may be covered to prevent injury to the player.

If desired, the rod 13 and legs 14 may be integrally formed.

The member 15 and also member 14 may be made adjustable on the rod 13 to enable the use of my device on violins of different sizes.

It is of course obvious that my invention may be modified in various ways without departing from the spirit of my invention. I therefore do not wish to restrict myself to the details described and shown.

What I claim is:—

1. In a violin attachment, a hand guide comprising a member adapted to extend below the neck portion of a violin and be attached to the violin so as to bear against the side portion of the wrist of the player's hand and means adjustably mounted on said member so as to bear against the inner part of said wrist, said member being suspended from the violin by pairs of arms fixed to the

ends of said member, one pair embracing the neck portion of the violin and another pair suspended from the body thereof.

2. In a violin attachment, a hand guide comprising a member adapted to extend below the neck portion of a violin and be attached to the violin so as to bear against the side portion of the wrist of the player's hand and means adjustably mounted on said member so as to bear against the inner part of said wrist, said member being suspended from the violin by two pairs of arms attached to said member, one pair embracing the head of the neck portion of the violin and the other pair engaging the body portion of said violin, said pairs of arms each being made of pieces of resilient wire coiled around said member.

3. In a violin attachment, a hand guide comprising a member adapted to extend below the neck portion of a violin and be attached to the violin so as to bear against the side portion of the wrist of the player's hand and means adjustably mounted on said member so as to bear against the inner part of said wrist, said adjustable means consisting of an arm frictionally mounted on said member to extend laterally from said member and slantingly toward the body portion of the violin.

4. In a violin attachment, a hand guide comprising a member adapted to extend below the neck portion of a violin and be attached to the violin so as to bear against the side portion of the wrist of the player's hand and means adjustably mounted on said member so as to bear against the inner part of said wrist, said adjustable means consisting of an arm formed with a sleeve slidably borne on said member, said arm projecting laterally from said member and slantingly toward the body portion of the violin.

5. In a violin attachment, a member adapted to extend below the neck portion of a violin, means for suspending said member from the head of said neck portion and the violin body, means on said member adapted to bear against the inner portion of the wrist of the player's hand, when the latter is used to stop the violin strings, and prevent the swinging of said hand at said wrist, said member being adapted to bear against the side of said hand to prevent its swinging under said neck.

6. In a violin attachment, a rod like member adapted to extend parallel to the neck member of a violin and below it, means for suspending said member from the head of said neck portion and the violin body, means slidably mounted on said member adapted to bear against the inner portion of the wrist of the player's hand and prevent swinging of said hand at said wrist, said member being adapted to bear against the side of said

hand to prevent its swinging under said neck.

7. In a violin attachment, a member adapted to extend below the neck portion of a violin, means for suspending said member from said neck portion and the violin body, means on said member adapted to bear against the inner portion of the wrist of the player's hand when the latter is used to stop the violin strings and prevent the swinging of said hand at said wrist, said member being adapted to bear against the side of said hand to prevent its swinging under said neck.

In testimony whereof I affix my signature.
